(57) **CLAIM**

The ornamental design for a connector, as shown and described.

DESCRIPTION

FIG. 1 is a top, front, and left side perspective view of a connector showing our new design;

FIG. 2 is a top, back, and left side perspective view thereof; FIG. 3 is a top, front, and right side perspective view thereof; FIG. 4 is a bottom, front, and left side perspective view thereof;

FIG. 5 is a front view thereof;

FIG. 6 is a back view thereof;

FIG. 7 is a right side view thereof;

FIG. 8 is a left side view thereof;

FIG. 9 is a top view thereof;

FIG. 10 is a bottom view thereof;

FIG. 11 is a close-up top, front and left side perspective view taken from the sectional designation in FIG. 1; and,

FIG. 12 is a close-up bottom, front, and left side perspective view taken from the sectional designation in FIG. 4.

The broken lines in the drawing views are included to show portions of a connector that form no part of the claimed design. The dot-dash lines in the drawings view are included to show the boundary between claimed and unclaimed subject matter and form no part of the claimed design.
